UNITED STATES PATENT OFFICE

ARCHIBALD REYNOLDS, OF COLTS NECK, NEW JERSEY

BAG HOLDER

Application filed December 22, 1930. Serial No. 504,002.

This invention relates to improvements in bag filling devices in general and more particularly to a device of this kind adapted to be used to fill paper bags such as are commonly employed where fruits and vegetables are sold at retail.

A feature of the invention is that the construction of the device is such that a bag of the paper variety may be readily supported therein in an open position without being attached thereto in any way.

A further feature of the invention is that bags of various sizes may be conveniently used with the same device.

15 An object of the invention is to provide a suitable means by which bags of various sizes may be quickly and conveniently positioned for filling and thus retained in an open position to permit the introduction of merchandise.

20 Various other objects and advantages will be in part obvious from an inspection of the accompanying drawings and a careful consideration of the following particular description and claims of one form of mechanism embodying my invention.

In the drawings:

Figure 1 is a perspective view of the present invention.

30 Figure 2 is a vertical section of the structure shown in Figure 1.

Figure 3 is a fragmentary view partly in section of an alternative structure.

With reference to the drawings, 10 designates a base upon which is securely mounted an upright semi-cylindrical member 11 formed substantially U shaped in cross section, so as to provide an open front in elevation as shown in Fig. 1.

40 A plurality of tie members 12 and 13 are secured to the member 11 as shown to give it the necessary rigidity, the lower one 12 being further employed to support a swingable shelf 15 which engages the tie member by means of a suitable latch 16. The shelf 15 is hinged at 17 and it will be seen that said shelf is conformed approximately to the curvature of the rear wall portion of the member 11 so that it may readily rest thereagainst in its lowered position as shown in Fig. 2, thus elimi-

nating any tendency on its part towards interference with a bag that may be placed in the device for filling. This shelf in its raised position is adapted to support a bag 18 of about one half the size of the full length bag 19 shown in Fig. 2.

To the rounded upper rear edge of the member 11 there is secured by means of a hinge 20 a funnel 21 which can be swung about said hinge so that the bag may be readily inserted, 60 after which, said funnel may be swung to a position partly within the mouth of the bag. A semi-circular member 14 secured to the member 11 in the position shown, provides a cylindrical upper opening for the device so that the four corners of the bag may be supported and suitably positioned therein for the introduction of the funnel 21.

15 The operation of the device is as follows:

The funnel is first swung back out of the 70 way and the bag inserted through the cylindrical opening to rest either upon the shelf 15 or the base 10 according to the length of the bag. The funnel is then swung into the mouth of the bag and the bag filled with whatever merchandise desired after which the funnel is returned and the bag lifted from the holder.

25 The invention can most economically be constructed of galvanized sheet iron, but any 80 other material may be used if found more convenient.

With reference to Fig. 3 there is shown an alternative construction in which a weighing scale 22 preferably of the spring balance type 85 has been introduced within the lower portion of the member 11 so as to normally rest upon the base 10.

30 The vertical member 11 should in this case be made proportionately longer so that a full sized bag may rest upon the platform 23. Suitable finger screws 24 are secured to the weighing scale and extend through slots 25 which are of such length that the scale may be readily raised to an intermediate position and there secured by means of said screws for the purpose of supporting a bag of lesser size.

35 Variations may be resorted to within the scope of the invention and portions of the 100

improvements may be used without the others whilst not departing from the spirit of the invention.

Having thus described my invention, I claim:

1. In a device of the character described, the combination of a vertically disposed member formed substantially **U** shaped in cross section so as to provide an open front, transversely disposed tie elements secured across the open front of said member, a shelf having one end pivotally connected to the rear portion of said member and adapted to have its movable end supported upon one of said tie elements, and a funnel pivotally mounted adjacent the upper edge of said member in a manner as to permit the same to be swung into or out of the upper open portion of said member.
2. In a device of the character described, the combination of a vertically disposed member formed substantially **U** shaped in cross section so as to provide an open front, a base on which said member is mounted, transversely disposed tie elements secured across the open front of said member, a semi-circular element secured adjacent the upper edge of said member in a manner as to provide in conjunction therewith a circular wall adapted to support the corners of a bag placed within said member against lateral displacement, and a funnel mounted adjacent the upper edge of said member so that the same may be swung into or out of the opening formed by said circular wall.
3. In a device of the character described, the combination of a vertically disposed member formed substantially **U** shaped in cross section so as to provide an open front and an upper opening, a base support adapted to sustain a full length bag within said member, a removable shelf adapted to sustain a lesser sized bag; said shelf being disposed intermediate said base and the upper extremity of said member, and a funnel adapted for movement into or out of said upper opening.
4. In a device of the character described, the combination of a vertically disposed member formed substantially **U** shaped in cross section so as to provide an open front and an upper opening, a base at the lower extremity of said member adapted to support a bag of equal length to said **U** shaped member, a swingable shelf disposed intermediate said base and said upper opening which is adapted to support a bag of lesser length, and a funnel adapted for movement into the mouth of a bag of either length.
5. Signed at Freehold, in the county of Monmouth and State of New Jersey this 18th day of December, 1930.

ARCHIBALD REYNOLDS.
